ANNEALING FURNACE

Lee Wilson, Cleveland, Ohio

Application July 25, 1933, Serial No. 682,092

9 Claims. (Cl. 263—42)

This invention relates broadly to annealing furnaces, and more particularly to a furnace for heat treating or annealing metal sheets, strips, coils, plates, and the like, in a controlled and 5 non-oxidizing atmosphere.

The present invention aims to provide a furnace in which the material may be efficiently heat treated or annealed by exposing the same in the furnace, free from any covering whatsoever, in an atmosphere heated by radiation and free of products of combustion or other harmful gases.

A further object of the invention is to provide a furnace in which the material may be treated 15 in a fraction of the time consumed under existing methods and with present structures, the annealing also being accomplished with the consumption of a minimum amount of fuel.

A further object is to provide individually controlled heat radiating units for regulating the temperature of the furnace, as may be desired.

A still further object is to provide a furnace whose confining walls are composed almost entirely of insulating or refractory material, there- 25 by affording substantially low radiation losses; lower heat storage in the walls, and extremely light weight.

With these and other objects in view, the invention resides in the features of construction, 30 arrangement of parts, and combinations of elements, which will hereinafter be described, reference being had to the accompanying drawings, in which—

Figure 1 is a vertical cross sectional view of a 35 furnace constructed in accordance with my invention, the section being taken on line A—A, Fig. 3;

Figure 2 is a vertical cross sectional view of the removable bell or hood removed from the 40 stationary base or foundation, a portion being broken away; and—

Figure 3 is a section on line B—B, Fig. 1.

The furnace is preferably composed of two 45 principal parts—a permanent base or foundation, and a movable bell or muffle type heating furnace.

The base is permanently and stationarily constructed on the floor level and consists of a foundation 1 of common brick upon which is 50 superimposed the base 2, the latter being made of an appropriate insulating material. This construction provides a raised platform, rectangular in top plan view and whose plane dimensions are greater than the sheets 3 to be annealed. En- 55 circling said base and at a spaced distance there-

from is a U-shaped channel 4, designed to contain oil, water, molten lead, or other appropriate sealing agent.

The movable bell or muffle type furnace herein described is also rectangular in shape and consists of two side walls 5^a, two end walls 5^b, and a roof or crown 5^c, all of refractory material, the bell being housed in a metal casing 6. The inside dimensions of the furnace exceed the corresponding dimensions of the elevated platform, as shown in Fig. 1, the lower ends of said furnace being shaped to correspond with the base 2, and the lowermost edge of the furnace resting upon the floor level about the foundation when in operating position.

A plurality of vertically extending tubes 7 are positioned along the two parallel side walls 5^a, the upper ends thereof being reduced somewhat in diameter and protrude outwardly through the crown 5^c, dampers 8 being present in each of said tubes. Said tubes 7 are maintained in rigid relation interiorly of the furnace by means of hooks 9 which embrace said tubes, the shanks of said hooks extending outwardly through the side walls of the furnace and being fastened by nuts.

The lower ends of said tubes 7 are connected to and supported by elbow joints 10, the opposite right angle end of each elbow being connected to a sleeve 11 which extends in length throughout the thickness of the furnace walls, terminating exteriorly of the furnace wall. Each of said sleeves 11 is composed of a hollow tubular casing lined with refractory or insulating material. As shown in the drawings, the elbows 10 rest upon a ledge 12 formed interiorly of the furnace wall adjacent the bottom.

Firing into each of the sleeves 11, which latter, in conjunction with the elbows 10, serve as combustion tunnels, is an individual gas or oil burner 13, supplied with fuel through the manifolds 14 carried by the furnace, as by means of the brackets 15. A valve 16 is provided with each burner whereby the operation of the latter may be regulated.

In practice, the material 3, as steel sheets, to be treated is stacked upon the raised base 2 and the furnace is then lifted and placed over and about the base 2 by means of an overhead lifting crane, supporting eyes 17 being provided at opposite corners on the furnace to facilitate moving. When lowered about the base 2, the outwardly and downwardly extending annular skirt 18, which is attached to the furnace in encircling relation adjacent the lower edge, is positioned in the oil filled channel 4 so as to effectually seal

the inside of the furnace from the atmosphere, as depicted in Fig. 1. The burners 13 are then ignited and the burning of the fuel in the sleeves 11 and elbows 10 results, of course, in the creation of heated gases. These heated gases pass upwardly and outwardly through the tubes 7, heating the latter in travel, which heat, in turn, is radiated to the interior of the furnace, where it is absorbed by the material therein placed for treatment. Obviously, the furnace is continuously fired until such time as the material is brought up to the required temperature and there maintained for a predetermined period of time.

When the heating cycle is completed, the burners are closed and the furnace may be cooled by passing air through the tubes, or it may be cooled solely by loss of heat through radiation, after which the furnace is lifted and removed to permit removal of the material, after which the operation may be repeated.

Upright pins 20 may be stationarily fixed to the floor and project upwardly therefrom at opposite sides of the base so as to receive thereabout loops or eyes 19 extending outwardly from the furnace, this arrangement affording means for guiding the latter to correct seating position with respect to the base.

From the above description it will be noted that the furnace described provides a structure in which annealing may take place efficiently, economically and with considerable saving of time. It will also be observed that the construction presented affords an annealing chamber in which substantial variations in temperature at different points of the furnace is eliminated. Under existing methods, the top of the furnace or the pack is always hotter than the bottom, this difference at times amounting to as much as 500° F. This condition produces sheets that are not uniform in anneal, many being over-annealed and many having to be returned for further annealing. One reason for the difference in temperature in the top and bottom of the pack or furnace is due to the concentration of weight or mass that must be heated adjacent the bottom. In box annealing, the sheet supporting plate-like tray, ball rollers, and sand seal are located at the bottom, and these elements alone contribute one-fourth to one-half of the total mass to be heated to annealing temperature. Too, as is well known in the art, it is difficult to force and maintain heat adjacent the bottom of any furnace.

Due to the fact that the flame fired from the burners 13 of the herein described structure is projected through the sleeves 11, elbows 10 and upwardly into the tubes 7, the highest temperature will, of a consequence, be adjacent the lower portion of each tube, which high temperature is there radiated from the tubes inwardly to the lower part of the pack or furnace, thus compensating or balancing the heat which naturally rises to the top, resulting in evenly distributed temperature throughout the entire furnace. The absence of heat absorbing material on the bottom of the furnace contributes in a large measure to the retention of heat near the bottom.

While I have herein described the furnace as being of rectangular shape, it will be understood that other and different shapes may more readily be adapted for certain purposes. For instance, a circular shape may be utilized for the annealing of coils and the like.

It is thought that the construction and operation of the furnace and the function of its various elements will readily be understood from the

foregoing description. Further, while I have described the invention more or less in detail, it will be understood that I do not limit myself to details of construction and arrangement of parts except as may be required by a fair interpretation of the terms of the appended claims.

What is claimed is:—

1. In an annealing furnace, a base, a bell having side and end walls and a roof movably mounted on the base, a series of vertical heating tubes in the bell disposed along each side wall of the latter and having upper open ends extending through the roof and having lateral portions at their lower ends opening through the side walls at the lower parts of the latter, and a manifold connected to each side wall of the bell and having a series of burners, one for each tube, which burners are in register with the open ends of the lateral portions of the tubes, the upper ends of the tubes being attenuated and having dampers disposed exterior of the roof.

2. In an annealing furnace, a base, a bell having side and end walls and a roof movably mounted on the base, a series of vertical heating tubes in the bell disposed along each side wall of the latter and having upper open ends extending through the roof and having lateral portions at their lower ends opening through the side walls at the lower parts of the latter, and a manifold connected to each side wall of the bell and having a series of burners one for each tube which burners are in register with the open ends of the lateral portions of the tubes.

3. In an annealing furnace, a base, a bell having side and end walls and a roof cooperable with the base, a series of vertical heating tubes in the bell disposed along each side wall of the latter and having upper open ends extending through the roof and having lateral portions at their lower ends opening through the side walls at the lower parts of the latter, and a series of burners one for each tube which burners are in register with the open ends of the lateral portions of the tubes.

4. In an annealing furnace, a base, a bell cooperable with the base, a series of vertical heating tubes in the bell disposed along opposite sides of the latter and extending substantially throughout the height of the bell, and having portions extending through said sides of the bell, and means for supplying heat to each of said portions of the tubes.

5. In an annealing furnace, a base, a bell cooperable with the base, a series of vertical heating tubes in the bell disposed along opposite sides of the latter and extending substantially throughout the height of the bell, and having portions extending through said sides of the bell, and a burner for each tube in register with said portions thereof.

6. In a heat treating furnace, a base, a bell located over said base, a series of vertical heating tubes in the bell disposed along each side wall of the latter and having their upper ends extending exteriorly of the bell adjacent the roof of the latter, and a series of gaseous fuel burners, one for each tube, whereby each tube may be individually fired.

7. In a furnace, the combination with a heating chamber and a hearth therefor, a plurality of vertical extending tubes disposed along each side wall of the heating chamber, the lower ends of said tubes entering the furnace at a point below the level of the hearth and the upper ends extending exteriorly of the furnace at a spaced

- distance above said hearth, and a gaseous fuel burner located in the lower end of each of said tubes whereby each tube may be independently fired.
5. 8. In a furnace, a base, a movable bell cooperable with the base, a series of vertical heat-radiating tubes in the bell disposed along the sides of the latter and extending substantially throughout the height of the bell and having portions thereof extending exteriorly of the furnace, and means including gaseous fuel burners for supplying heat separately to each of said portions of the tubes.
- 10

9. In a furnace, a heating chamber, a series of vertically disposed heat-radiating tubes arranged along the walls of said heating chamber, and having their lower portions extending exteriorly of the furnace adjacent the hearth, a gaseous fuel burner for each tube in register with each of said portions whereby controlled heat treating temperatures may be individually introduced into each of said tubes.
